UNITED STATES PATENT OFFICE

ALEXANDER R. KANNÉ, OF BROOKLYN, NEW YORK

DESIGN FOR AN ELECTRIC PLUG MEMBER

Application filed June 27, 1931. Serial No. 40,342. Term of patent 7 years.

To all whom it may concern:

Be it known that I, ALEXANDER R. KANNÉ, a citizen of the United States, residing at 1640 Ocean Avenue, Brooklyn, county of Kings, New York, have invented a new, original, and ornamental Design for an Electric Plug Member, of which the following is a specification:

In the drawings:

Fig. 1 is a view in front elevation of a plug embodying my design, and

Fig. 2 is a side elevation thereof.

I claim:

The ornamental design for an electric plug member, substantially as shown.

ALEXANDER R. KANNÉ.
